Inventor:

Geo. R. Moore

United States Patent Office.

GEORGE RODNEY MOORE, OF PHILADELPHIA, PENNSYLVANIA.

Letters Patent No. 96,338, dated November 2, 1869.

IMPROVEMENT IN OVENS.

The Schedule referred to in these Letters Patent and making part of the same.

To all whom it may concern:

Be it known that I, GEORGE RODNEY MOORE, of Philadelphia, in the county of Philadelphia, in the State of Pennsylvania, have invented certain new and useful Improvements in Oven-Doors and Casings; and I do hereby declare that the following is a full and exact description thereof, reference being had to the accompanying drawings, and to the letters of reference marked thereon.

The object of my invention is to prevent, in the most effectual manner, heat radiation outward, from portable and other ovens, through the doors and casings. Also, to provide a cheap and durable oven-pyrometer.

Figure 1 is a plan view of the inside of an oven-door, and shows the arrangement of the pyrometrical levers.

Figure 2 is a plan view of the outside of the door, and shows, within the flanges *a a a a*, a panel of wood, *b*. Under this panel or casing of wood there is a quantity of paper over the iron body and frame-work of the door.

Figure 3 shows a cross-section of the same, *b* showing the wood, *c*, the paper, and *d*, the iron.

Figure 4 shows another kind of flange, *e*, more convenient for attaching casings to tin or sheet-iron ovens.

It is thus seen that the frame-works of the oven are made with suitable flanges for holding whatever non-

radiating materials it may be deemed best to use for casings; in this instance, several thicknesses of paper, overlaid with a panel of wood. Also, from fig. 4, that suitable flanges or rims, *e*, may be made separate for holding casings upon ovens that are not cast.

The operation of the pyrometrical levers is obvious. *A* vibrates upon a stationary pivot, and, having an extended leverage, a slight expansion of *B* will extend the index-lever *C* outward very perceptibly.

The paper and wood casings, above described, will, on first being heated, cause some smoke from the paper *c*, at which time it becomes partially charred, and then (in its charred state) performs its office admirably.

Having thus fully described my invention, What I claim therein as new, and desire to secure by Letters Patent, is—

1. The construction of oven-doors and sides, with casings of paper and wood, or their equivalents, substantially as and for the purpose herein set forth.
2. The pyrometrical levers *A B C*, arranged as herein shown, with oven-doors and sides encased, as above shown.

GEO. R. MOORE.
